[57] ABSTRACT

The mechanism includes a counter frame and a plurality of toothed counting wheels rotatably mounted on a common shaft and each having a respective heart-shape resetting cam fixed thereto. To reset the counting mechanism to zero, the cams are actuatable by respective zero setting fingers of a zero setting rake operable, against spring bias, by a resetting slide shiftable in the counter frame transversely of the counting wheel shaft. A plurality of counting wheel stepping pinions are mounted on a common shaft which is displaceable radially of the counting wheels. During zero setting of the counting wheels, the pinions are disengaged therefrom and are maintained in their respective angular orientations by fixed elastic tongues. The resetting slide includes a plate having a width substantially equal to the axial length of the counting wheel set, and the zero setting fingers are arranged in fixed positions on this plate. The plate has wall portions extending from its opposite longitudinal edges and mounting the common shaft of the pinions in parallel with the common shaft for the counting wheels. The common pinion shaft is mounted in elongated slots so as to be shiftable relative to the slide against frictional resistance produced by spring pressure. Releasable detent means are provided to latch the slide in a position in which the pinions are engaged with the respective counting wheels.

ZERO SETTING ROLLER COUNTING MECHANISM

FIELD AND BACKGROUND OF THE INVENTION

This invention relates to a zero setting roller counting mechanism including heart-shape resetting cams each connected to a respective counting wheel and which, for resetting, are actuated by zero setting fingers on a zero setting rake operable, against spring bias, by a resetting slide which can be shifted within a counter frame transversely to the common axis of the counting wheels. The counting mechanism further includes stepping pinions mounted on a common shaft displaceable radially relative to the counting wheels and which pinions, during zero setting of the counting wheels, are disengaged therefrom and maintained in their respective angular orientations by means of fixed elastic tongues.

Zero setting roller counting mechanisms of this type are known. For example, German provisionally published application No. 2,136,712 discloses a zero setting roller counting mechanism in which the resetting slide consists of a plate which is mounted in the counter frame below the counting wheels so as to be shiftable, and which, in its rest position, projects from the front side of the counter frame and may be pushed manually into the counter frame through a certain distance. The stepping pinions are freely rotatable on a shaft which is mounted so as to be displaceable in slots provided in the side walls of the counter frame, and these slots extend radially relative to the stepping pinions. The displacement of the shaft in the slots of the side walls of the frame is effected by lateral sliding guides provided for the resetting plate, which has guiding surfaces which are oblique to its direction of displacement.

In the arrangement of German provisionally published application No. 2,136,712, the zero setting fingers which, during resetting, act upon the heart-shape cams of the counting wheels, are secured, with the corresponding axial spacing, to a bow which is parallel to the common axis of the counting wheels and pivotally mounted on the common shaft of the pinions. This bow is provided with a forked claw in which an operating cam of the resetting plate engages in order to effect a pivotal movement of the zero setting fingers during the resetting movement of the plate. The elastic tongues, serving to maintain the stepping pinions against rotation during the zero setting operation, are also arranged on the bow having the resetting fingers, so that the stepping pinions, owing to their radial displacement with respect to the counting wheels, come into contact with the elastic tongues as soon as they are disengaged from the teeth of the respective counting wheels. The zero setting fingers, the elastic tongues, the bow, and the forked claws are made of synthetic material and in one piece, and so is the resetting plate with its slide guides and the operating cam.

There are other known roller counting mechanisms in which the resetting part comprises a slider mounted in a side wall of the counter frame and actuating, on the one hand, by means of a cam, a resetting rake and, on the other hand, a bridge for shifting the pinion shaft in the respective seating slots therefor. The elastic tongues, for maintaining the stepping pinions against rotation, are secured to a web of the counter frame.

As such roller counting mechanisms are manufactured, and also needed, in large quantities, the impor-

tant requirement to be met, aside from the basic demand for reliability in service, is to reduce the manufacturing costs as much as possible. It is for this reason that, for some time, many parts of roller counting mechanisms have been made of synthetic materials, by injection molding, and the number of component parts has been reduced to a minimum. However, and in spite of these steps, in known counting mechanisms, the desired cost reduction has not been capable of being obtained because of the still too high labor costs for assembly.

SUMMARY OF THE INVENTION

This invention is directed to the problem of providing a zero setting roller counting mechanism of the type mentioned above and which, while meeting all requirements as to its reliability in operation, can be manufactured at a substantially less expensive than known roller counting mechanisms.

15 In accordance with the present invention, this problem is solved by providing a resetting slide in the form of a plate extending throughout the axial distance of the counting wheels set, and zero setting fingers are arranged in a fixed position on this plate. Both longitudinal edges of the plate have wall portions in which the shaft of the stepping pinions is mounted parallel to the shaft rotatably supporting the counting wheels.

20 By such an arrangement, the time necessary to assemble the counting mechanisms is substantially reduced because the stepping pinions may be mounted on their shaft, and the shaft may be placed in its seats, outside the counter frame. Additionally, the zero setting fingers, as they are an integral part of the resetting slide, need not be mounted separately and are introduced into the frame along with the resetting slide.

25 Even if it were necessary to manufacture the zero setting fingers, in a known manner, in the form of a separate comb-shape part to be secured to the plate or resetting slide, for example, by means of screws or rivets, the assembly time would still be considerably more favorable than with known counting mechanisms. However, it is more expedient to make the slide in one piece with the lateral wall portions and the zero setting fingers, and preferably of synthetic material, because, when this is done, the time for securing the fingers to the slide is saved and the whole assembly operation consists merely in loosely inserting the resetting slide into the counter frame and mounting the shaft for the counting wheels in the frame.

30 An important feature of the invention is that the pinion shaft is mounted in slots in the wall portions, so as to be shiftable, against the friction produced by a spring pressure, with the resulting advantage that, as compared to the distance covered by the resetting slide having the zero setting fingers, the stepping pinions are shifted through a distance which is shorter, by the length of the slots receiving the pinion shaft, and that, in each case, the stepping pinions are moved immediately when the resetting slide starts to move. Consequently, the stepping pinions are positively disengaged from the teeth of the counting wheels before the zero setting fingers engage the heart-shape resetting cams of the counting wheels.

35 At the return of the resetting slide into its rest position, the stepping pinions are re-engaged with the respective counting wheels before the zero setting fingers disengage from the heart-shape resetting cams.

40

50

55

60

65

Taking into consideration the requirement for both saving as much space as possible and providing a most simple assembly operation, it is advantageous to produce the friction forces by providing, on the wall portions of the resetting slide, bar springs, leaf springs, or similar springs which press the pinion shaft against a longitudinal surface of the respective slot.

An object of the invention is to provide an improved zero setting roller counting mechanism.

Another object of the invention is to provide such a zero setting roller counting mechanism in which the assembly expense is very substantially reduced.

A further object of the invention is to provide such a zero setting roller counting mechanism which operates reliably in practice.

Another object of the invention is to provide such a zero setting roller counting mechanism in which the resetting slide is integral with the zero setting fingers and supports a shaft mounting the stepping pinions whereby the resulting unitary assembly may be readily inserted into a counter frame.

For an understanding of the principles of the invention, reference is made to the following description of a typical embodiment thereof as illustrated in the accompanying drawings.

BRIEF DESCRIPTION OF THE DRAWINGS

In the Drawings:

FIG. 1 is an isometric view of a resetting slide of a roller counting mechanism in accordance with the invention;

FIG. 2 is a partial front elevation view, partly in section, of the roller counting mechanism embodying the invention;

FIG. 3 is a sectional view taken along the line III—III of FIG. 2;

FIG. 4 is a sectional view taken along the line IV—IV of FIG. 3; and

FIG. 5 is a sectional view taken along the line V—V of FIG. 3.

DESCRIPTION OF THE PREFERRED EMBODIMENT

Referring to the drawings, a roller counting mechanism embodying the invention comprises a counter frame structure 1 which is an integral piece of synthetic material and includes a bottom wall 2 as well as side walls 3 and 4 which are connected to each other, on the front side 5 of the counting mechanism, by an upper bar 6. Counter frame 1 is open both at its front side 5 and at its top 7.

In the rear part of counter frame 1, which has not been shown in the drawings, an electromagnet is located and serves, in a known manner, to drive the counter by pulse sequences. The armature of this electromagnet actuates a shifting fork, which has not been shown, which engages a star wheel of the first counting decade. These parts have not been shown in the drawings as they are common to zero setting roller counting mechanisms of the type to which the present invention is directed.

The roller counting mechanism includes counting wheels 9 each having affixed thereto a respective heart-shape resetting cam 8, wheels 9, with their cams 8, being freely rotatably on a common counting wheel shaft 10 mounted in axially aligned bores 11 and 12 provided in the respective side walls 3 and 4. For rea-

sons which will be explained hereinafter, the inner surfaces of side walls 3 and 4 are provided with respective recesses 13 and 14, each having a vertical front edge 15 and an oblique rear edge 16, both edges being tangential to the respective bore 11 and 12. On each side of the set of counting wheels 9, and between the end counting wheels and the respective side walls 3 and 4 of frame 1, shaft 10 supports spacer sleeves 17 and 18.

A resetting slide 19 is supported on the bottom 2 of frame 1 between side walls 3 and 4, and is mounted so as to be shiftable along side walls 3 and 4 against the bias of a spring. As best seen in FIG. 1, resetting slide 19 includes a plate 20 having, on its front side 21, a projection 22 and a row of vertically extending laterally spaced zero setting fingers 23 which are spaced laterally uniformly along front side 21. Plate 20 further includes lateral wall portions 24 and 25, each extending along a respective side edge of plate 20, and each being formed with respective horizontal slots 26 and 27 as well as with respective horizontal upper guide edges 28 and 29.

Slots 26 and 27 receive shaft 30 of the stepping pinions, and shaft 30 extends, on both sides, outwardly of the outer surfaces of the wall portions 24 and 25. At least one end of shaft 30 is flattened, and preferably both ends, to prevent rotation of shaft 30. On the outer surfaces of wall portions 24 and 25, bar springs 32 are secured at one end to pins 31, with their opposite ends being bent in the shape of a hairpin whose upper arm 34 engages against the respective end of shaft 30 thereby to press the flattened end of shaft 30 against the upper edges 35 and 36, respectively, of slots 26 and 27. The lower arm of the hairpin rests against a projection 37. With this arrangement, a frictional coupling is established between shaft 30, for the stepping pinions, and resetting slide 19. The flattened end or ends of shaft 30 provide a greater resistance to rotation of the shaft as compared to mere frictional resistance against the edges of slots 26 and 27.

As best seen in FIG. 3, the opposite ends of shaft 30 extend into guide recesses 38 and 39 formed on the inner surfaces of the respective side walls 3 and 4. The bottom surfaces 40 and 41 of the respective recesses 38 and 39 serve to limit the axial movement of shafts 30, while the respective vertical front edges 42 and 43 thereof serve as a stop for shaft 30, thus preventing the loose stepping pinions 44, mounted on shaft 30, from being drawn, owing to the spring bias to which resetting slide 19 is subjected, too far into engagement with the counting wheels 9.

Vertically extending elastic tongues 45 are provided at a certain distance from shaft 10 for the counting wheels, and are arranged in a row parallel to the axis of shaft 10 or to the axis of bores 11 and 12 of the respective side walls 3 and 4. Tongues 45 serve to maintain the stepping pinions 44 against rotation when the same are disengaged from counting wheels 9. These tongues 45 are made of synthetic material and are integral with counter frame 1, so that no subsequent mounting or securing of the tongues is necessary. The cross-sections of tongues 45 are of such dimensions that the tongues are sufficiently rigid and sufficiently elastic to be able to engage stepping pinions to prevent rotation of the pinions during the zero setting operation. This is important in order to return stepping pinions 44 again into operative engagement with the respective counting wheels 9 in the same relative angular

orientation, as soon as the zero setting has been terminated. Adjacent both edges of the projecting part 22 of the plate 20 of slide 19, two approximately semi-circular grooves 46 and 47 are formed in the bottom surface of plate 20, and these grooves extend parallel to the lateral walls. Below each of the grooves, elongated openings 48 are provided in the bottom two of counter frame 1, and these openings serve to receive return springs 49 of resetting slide 19. As best seen in FIG. 4, springs 49 engage, at one end, hooks 50 provided on bottom 2 of frame 1 and, at the other end, hooks 51 provided on plate 20, the hooks 51 extending into the openings 48 of bottom 2 of frame 1.

Approximately at the center of plate 20, a stop notch 52 is formed in the bottom surface thereof, and a latch 53 of a stop spring is engaged in this notch when resetting slide 19 is in its rest position illustrated in FIG. 5. The stop spring 54 and latch 53 are formed integrally with the bottom 2 of counter frame 1, and are surrounded by a U-shape opening 55 as shown in dotted lines in FIG. 3.

The successive operations in assembling the roller counting mechanism of the invention will now be described. As a first step, the necessary number of stepping pinions 44 and spacer sleeves 56 and 57 are mounted on shaft 30 which is then introduced into slots 26 and 27 of resetting slide 19. Bar springs 32 may be mounted either before or after the introduction of shaft 30 into slots 26 and 27. Following this, the preassembled resetting slide 19 is inserted into counter frame 1 from above, so that its projection 22 extends from the front side 5 of the counter frame and plate 20 rests loosely on bottom 2 of frame 1. At the same time, the opposite protruding ends of shaft 30 are received in the recesses 38 and 39 provided in the respective side walls 3 and 4 of counter frame 1, so that springs 49, which have previously been secured to hooks 50 of frame 1, can be immediately secured to hooks 51 of plate 20. It then remains to bring the counting wheels into their respective positions, and this is effected in a manner which will now be explained.

Because counting wheels 9, after the digits have been applied on the cylindrical peripheries thereof, must, in any case, be checked visually, an auxiliary shaft is used for this purpose and the counting wheels, in the necessary number and succession, are mounted on this shaft. The length of the auxiliary shaft is such as to just fit in the space provided by the two recesses 13 and 14 formed in the respective side walls 3 and 4 of counter frame 1. Together with counting wheels 9 and, perhaps, a blank roller, the two spacer sleeves 17 and 18 are also mounted on the auxiliary shaft before the final mounting of the whole set. Then the auxiliary shaft is introduced into the recesses 13 and 14 from above so that, by virtue of the guide edges 15 and 16 of the recesses 13 and 14, which are tangential to the respective bearing bores 11 and 12, the auxiliary shaft is automatically axially aligned with bores 11 and 12. Thereafter, the auxiliary shaft is replaced by the true counting wheel shaft 10, whose length corresponds to the distance between the outer surfaces of side walls 3 and 4. This is effected by pushing shaft 10, from the outside, through one of the bores 11 and 12, which displaces the auxiliary shaft out through the other bore.

Thus, it is no longer necessary to mount counting wheels 9 and stepping pinions 44 individually on their respective shafts in counter frame 1. The entire assem-

bly of the counting mechanism requires less manipulation and thus a very considerably reduced work time. Furthermore, a perfect functioning of the assembled mechanism is assured.

5 While lateral guidance of resetting slide 19 in frame 1 is assured by side walls 3 and 4, slide 19 is guided, in the vertical direction, on the one hand by bottom 2 of frame 1 and, on the other hand, by the horizontal guide edges 28 and 29 which slide on spacer sleeves 17 and 18 of shaft 10, as shown in FIG. 2.

As soon as resetting slide 19 starts to be shifted, in the direction of arrow 58, from its rest position, shown in FIG. 5, to its final zero setting position, shown in FIGS. 3 and 4, the individual stepping pinions 44 are disengaged from the respective counting wheels 9 even before zero setting fingers 23 come into contact with the respective heart-shape resetting cams 8. This is due to the fact that shaft 30 for stepping pinions 44 which, in the rest position of resetting slide 19, occupies the position shown in FIG. 5 in which it is engaged against the rear ends of slots 26 and 27 provided in the respective wall portions 24 and 25, maintains this position owing to the frictional coupling effected by bar springs 32. When slide 19 is shifted further in the direction of arrow 58, stepping pinions 44 engage and are held against rotation by elastic tongues 45, and shaft 30 is prevented from further motion and is overtaken by slide 19. By this relative movement between shaft 30 and slide 19, shaft 30 is displaced in slots 26 and 27 until it engages the front edges thereof. A small additional overstroke results in engaging zero setting fingers 23 completely against the base portions of heart-shape cams 8, all of the elastic tongues 45 being at the same time slightly deflected.

After releasing resetting slide 19, return springs 49 pull slide 19 back toward its rest position. Again, owing to the action of the friction coupling, stepping pinions 44 re-engage the respective counting wheels 9 at the

40 What is claimed is:

1. In a zero setting roller counting mechanism of the type including a counter frame, a plurality of toothed counting wheels rotatably mounted on a common counting wheel shaft and each having a respective heart-shape resetting cam fixed thereto, the cams, for resetting of the counting mechanism to zero, being actuatable by respective zero setting fingers of a zero setting rake operable, against spring bias, by a resetting slide shiftable in the counter frame transversely of the common shaft of the counting wheels, and a plurality of counting wheel stepping pinions mounted on a common pinion shaft which is displaceable radially of the counting wheels, the stepping pinions, during zero setting of the counting wheels, being disengaged from the counting wheels and held against rotation by arresting elements: the improvement comprising, in combination, said resetting slide including a plate extending laterally through the axial length of the counting wheel set; said zero setting fingers being arranged in fixed positions on said plate; and wall portions extending from the opposite longitudinal edges of said plate and mounting said common pinion shaft in parallel relation to said common counting wheel shaft.

65 2. In a zero setting roller counting mechanism, the improvement claimed in claim 1, in which said plate is integral with said side wall portions and said zero setting fingers.

3. In a zero setting roller counting mechanism, the improvement claimed in claim 2, in which said plate is formed of a synthetic material.

4. In a zero setting roller counting mechanism, the improvement claimed in claim 1, in which said common pinion shaft is mounted in longitudinal slots in said wall portions so as to be shiftable longitudinally of said slots against the action of frictional forces produced by spring pressure.

5. In a zero setting roller counting mechanism, the improvement claimed in claim 4, in which the frictional forces are produced by finger-type springs secured on said wall portions and having free ends engaging the ends of said common pinion shaft and pressing the ends of said common pinion shaft against longitudinal surfaces of the respective slots.

6. In a zero setting roller counting mechanism, the improvement claimed in claim 1, in which said counter frame comprises a bottom and side walls extending upwardly from the opposite lateral edges of said bottom; each of said side walls being formed with an upwardly opening recess in its inner surface; said common pinion shaft being guided in said recesses.

7. In a zero setting roller counting mechanism, the improvement claimed in claim 1, including guide 25

sleeves on said common counting wheel shaft at opposite ends of the counting wheel set; said wall portions having horizontally extending guiding edges engaging said guide sleeves.

5 8. In a zero setting roller counting mechanism, the improvement claimed in claim 1, in which said counter frame is made of synthetic material and is formed integrally with said arresting elements for said stepping pinions.

10 9. In a zero setting roller counting mechanism, the improvement claimed in claim 1, in which said counter frame includes a bottom and side walls extending upwardly from the lateral sides of said bottom; said side walls being formed with axially aligned bearing bores

15 receiving said counting wheel shaft; the inner surfaces of said side walls being formed with upwardly opening guiding recesses extending from the upper edges of the side walls to said bearing bores.

10 10. In a zero setting roller counting mechanism, the improvement claimed in claim 1, in which the outer surface of said plate is formed with a notch; and a stop element elastically secured to said counter frame and engageable in said notch to retain said resetting slide in its rest position.
